UNITED STATES PATENT OFFICE.

FIORENTINO MACCARONE, OF ROCHESTER, NEW YORK.

SHOE AND METHOD OF MANUFACTURING THE SAME.

Application filed January 4, 1923. Serial No. 610,635.

To all whom it may concern:

Be it known that I, FIORENTINO MACCARONE, a citizen of the United States of America, residing at Rochester, in the county of Monroe and State of New York, have invented certain new and useful Improvements in Shoes and Methods of Manufacturing the Same, of which the following is a specification.

10 My invention relates to a shoe and method of manufacturing the same, and has for its principal object to make a turned shoe having the appearance when completed of a welt shoe.

15 The invention is an improvement on the construction disclosed in Patent No. 1,052,529, granted February 11, 1913, and has for a further purpose to afford a construction in which the sole possesses maximum stiffness and wearing qualities.

20 Still an additional object of my improvement is to afford a shoe of light weight, neat appearance, and which can be economically manufactured.

25 To these ends, the invention comprises the method and construction set forth in the following description, which is to be read in conjunction with the accompanying drawing, the novel features being pointed out in the claim following the specification.

In the drawing:

Figure 1 is a plan view of a sole made in accordance with a preferred embodiment of the invention;

35 Figure 2 is a transverse sectional view on the line 2—2 of Figure 1;

Figure 3 is a view similar to Figure 2, with the welt in position;

40 Figure 4 is an enlarged view similar to Figure 3 with the welt in position and the upper secured to the welt and sole, and

Figure 5 is an enlarged transverse sectional view showing the final position of the upper and sole after the upper is turned, and with the stiffening flange portion pressed down against the body portion of the sole.

45 The preferred method of procedure which I employ is to first slit a sole inwardly from its edge at a point beneath the top, as indicated at 1, and thereby afford a flange portion, indicated at 2, which is bent backwardly upon the body portion of the sole. In this manner, I form a channel 3 within 50 which the welt 4 is positioned to receive the upper.

An inclined cut 5 is made, commencing at a point inwardly of the flange portion 2, and extending downwardly to a point considerably beneath said flange portion. The upper 6 is then positioned as shown in Figure 4, and secured by stitches 7 which pass through the upper and welt and extend to the bottom of the inclined cut 5, said stitches being located in the body portion 65 of the sole at a point considerably beneath the flange portion. The flange portion 2 is then pressed down tightly against the body of the sole after which the upper is turned, as indicated in Figure 5, and the shoe 70 finished in the usual manner.

The flange portion 2, being integral with the body of the sole, acts to a marked degree as a stiffening means, and adds a substantial amount of strength and resistance 75 to the sole without increasing its weight. The flange portion 2 functions in the dual capacity of providing a channel for the welt and stiffening the sole, and is free to act efficiently as a stiffening member by reason of the upper being attached with stitches that pass through the body of the sole at a point considerably beneath the top of the sole and said flange portion 2. By 80 this arrangement, an extremely tight and 85 secure connection is made between the upper and the sole, the desirable light weight feature of the shoe is preserved, and by pressing the flange portion down upon the body 85 of the shoe, additional stiffness and wearing 90 qualities are imparted to the shoe without the necessity of a double sole.

A shoe made in this manner has practically the same appearance as a welt shoe, although it is much lighter in weight and 95 neater. It possesses wearing qualities superior to a welt shoe by reason of the extreme strength and stiffness imparted to the sole by the stiffening flange member 2, and as the sole can be trimmed and fitted closer 100 to the upper at the shank than in a welt shoe, a lighter and better appearing shank is produced, without losing the desired appearance of the welt shoe from the shank 105 forwardly to the toe.

I claim:

A turned shoe comprising a sole having a channel at its upper edge, a flange portion formed integral with the sole and bent backwardly from said channel so that it overlies 110 and contacts with the top of the body portion of the sole so as to stiffen the sole, the

flange portion being pressed against the body portion of the sole to set it, a welt arranged in said channel, the body of the sole having an inclined cut commencing inwardly of said backwardly bent flange portion and extending downwardly beneath the same, and an upper located above the welt and attached to the welt and sole by stitches extending through the welt and to the bottom of said inclined cut, said stitches extending through the body portion of the sole at a point considerably beneath said backwardly bent flange portion. 10

In witness whereof, I have hereunto signed my name.

FIORENTINO MACCARONE.
